UNITED STATES PATENT OFFICE.

THOMAS P. TAYLOR, OF BRIDGEPORT, CONNECTICUT.

BUSTLE.

SPECIFICATION forming part of Letters Patent No. 374,642, dated December 13, 1887.

Application filed July 25, 1887. Serial No. 245,181. (No model.)

To all whom it may concern:

Be it known that I, THOMAS P. TAYLOR, a citizen of the United States, residing at Bridgeport, in the county of Fairfield and State of Connecticut, have invented certain new and useful Improvements in Folding Bustles; and I do hereby declare the following to be a full, clear, and exact description of the invention, such as will enable others skilled in the art to which it appertains to make and use the same.

My invention relates to the class of folding bustles in which a series of ribs or bows are pivotally connected at the opposite sides of the bustle, and has for its object to provide improved means for returning the bustle to its distended position when pressure is removed after it has been forced to its folded or collapsed position.

Figure 1 is a perspective illustrating my improved bustle complete; Fig. 2, an enlarged detail perspective, the position of the bustle being reversed and the portion toward the point of view being removed, the bustle being in the distended position; Fig. 3, a similar view, the bustle being in the folded or collapsed position; and Fig. 4 is a view similar to Fig. 2, a flat spring being used instead of a wire spring, as in the other views.

1 denotes the side pieces; 2, the ribs or bows, the ends of which are pivotally secured to the side pieces, or to one of the other ribs; 3, the connecting-strip to which each of the ribs is attached; 4, the belt; 5, side strips connecting the belt with the side pieces, and 6 an adjusting-cord. These parts may all be of any preferred construction. I ordinarily, however, make them substantially as shown in the drawings.

In use when the wearer sits down the ribs fold upward toward the person of the wearer, the entire bustle being compressed into very small compass. In order to throw the ribs to the distended position when the wearer rises, various styles of independent springs have heretofore been used, which, however, have proved very unsatisfactory, for the reason that owing to the position in which the springs are placed when the bustle is collapsed the

power is partially and sometimes wholly lost, 50 the line of strain being a downward pull upon the ribs, which locks them in the collapsed position, instead of acting to throw them to the distended position. This is not pleasant, at best, and is frequently exceedingly embarrassing, as when the bustle locks it is necessary to give the skirts a vigorous shake to cause it to resume the distended position. In order to wholly overcome this objection, I have devised the novel construction and arrangement of springs which I will now describe.

7 denotes the springs, each of which consists of a pair of arms lying at a more or less acute angle to each other. When the springs 65 are made of wire, as in Figs. 1 and 2, I preferably provide a coil at the intersection of the arms.

In use I pivot the end of one arm of the spring to the side piece at a suitable distance 70 above the lower end thereof, and pivot the other arm to one of the lower ribs at a suitable distance from its pivotal point to the side piece. These points of attachment of the arms of the spring to the bustle are so 75 arranged relatively to each other that when the bustle is collapsed the arms are pressed directly toward each other, the pivotal points of the springs turning slightly as the bustle is compressed.

I preferably use a spring at each of the lower corners of the bustle, and connect their inner ends by a cord, 8, so that it is impossible for them to get out of operative position.

It will be seen that when my improved 85 bustle is collapsed the entire force of the spring acts to throw the bustle to the distended position as soon as pressure is removed, none of the power of the spring being lost, as is the case in every other style of bustle in which 90 independent returning-springs are used. The position of the springs when the bustle is in the collapsed position is clearly shown in Fig. 3, and the position in the distended position is clearly shown in Fig. 2.

Having thus described my invention, I claim—

A bustle consisting of side pieces, a series

of ribs pivotally secured thereto, springs having arms at an angle to each other, and coils at the intersection of the arms, one of the arms of each spring being pivotally attached 5 to a side piece and the other arm pivotally attached to one of the lower ribs, at a suitable distance from its pivotal point to the side piece, the bows of said springs projecting in-

ward toward each other, and a cord, 8, connecting the coils.

In testimony whereof I affix my signature in presence of two witnesses.

THOMAS P. TAYLOR.
